(57) **CLAIM**

We claim the ornamental design for a portion of a gun case, as shown and described.

DESCRIPTION

FIG. 1 is a side view of a portion of a gun case according to a first embodiment of the present invention.

FIG. 2 is a top view of the portion of a gun case shown in FIG. 1.

FIG. 3 is an end view of the portion of a gun case shown in FIG. 1.

FIG. 4 is a side view of a second embodiment of the portion of a gun case.

FIG. 5 is a top plan view of the portion of a gun case shown in FIG. 4; and,

FIG. 6 is an end view of the portion of a gun case shown in FIG. 4.

The broken lines are differentiated to clarify the claimed design. Even broken lines having dashes of uniform length define environmental structure, and uneven broken lines having a long dash—short dash—long dash pattern define boundaries of the claimed surfaces.
